HARRY R. MEYER AND LYNN G. RILEY, OF WILKINSBURG, PENNSYLVANIA, ASSIGNEES TO WESTINGHOUSE ELECTRIC & MANUFACTURING COMPANY, A CORPORATION OF PENNSYLVANIA.

CIRCUIT INTERRUPTER.

Application filed October 6, 1919. Serial No. 328,838.

Our invention relates to circuit interrupters and particularly to latching means for interrupters of the railway or enclosed arc-extinguishing type.

- 5 One object of our invention is to provide a circuit interrupter of the above indicated character that shall be adapted to be tripped either automatically or by the movement of its operating handle.
- 10 Another object of our invention is to provide a latching mechanism for a circuit interrupter of the above indicated character that shall be compact in structure, economical to manufacture, readily adjustable and
- 15 reliable in its operation.

Figure 1, of the accompanying drawings, is a plan view, with the cover removed, of a circuit interrupter embodying our invention, and Fig. 2 is an end view, partially in section

20 and partially in elevation, of the interrupter shown in Fig. 1.

An enclosing housing 1 is provided with a plurality of apertured lugs 2, extending laterally from its base, for the purpose of facilitating the mounting of the same on the ceiling or beneath the floor of a railway vehicle. A cover member 3 is provided for the housing 1, and a plurality of internal lugs 4 are provided for supporting the interrupter mechanism.

30 A plate 5, constructed of insulating material, is secured by screws 6 to the lugs 4 and has mounted thereon a stationary terminal member 7, an electromagnet 8, a pivotally-mounted operating member 9, a pivotally-mounted movable member 10, a latching device 11 and a calibrating device 12. The operating lever 9 is pivotally mounted on a post 13, upon which is also mounted the movable member 10, and has a contact-carrying member 14 pivotally connected thereto.

The calibrating device 12 consists of a knurled nut 38 secured to a screw 37 that has threaded engagement with a bushing 45 38^a, and is locked in position by a nut 38^b.

A stationary contact finger 15 is secured to the stationary contact terminal 7, and a contact finger 16 is secured to the contact-carrying member 14. A tension spring 17 is operatively connected between a stationary member 18 and the movable member 10, and a compression spring 19 is disposed between the contact-carrying member 14 and the movable member 10. A tension spring 20 is

disposed between an arm 21 that projects 55 from the lever arm 9 and a projection 22 on the latching device 11. This spring is always under tension and serves to maintain the latch in operative relation to the member 10 and the handle 9.

60 The movable member 10 is so constructed that, when the lever arm 9 is turned in a clockwise direction, it engages a portion 23 of the movable member 10, thereby moving the same to tension the spring 17, and compresses the spring 19. Thus, when the movable member 10 is actuated, the movable contact member 16 engages the stationary contact member 15 and, since the contact-carrying member 14 is pivotally mounted on the 70 member 10, the contact member 16 will have a sliding motion with respect to the contact member 15.

75 The latching device 11 comprises a spring-restrained member 24 that is pivotally mounted on a pin 25 near one end thereof, a latch portion 26 at its other end, and an interiorly threaded, intermediate, tubular portion 27. When the movable member 10 is moved to such position by the lever 9 that the contact members are in engagement, the member 24 will assume substantially the position shown in the drawings.

80 The electromagnet 8 comprises a magnetizable core member 28, a pivotally mounted armature 29, and a winding 30, one terminal of which is operatively connected to the contact-carrying member 14, and the other terminal of which is connected to a conductor 31 that is adapted to pass through a bushing 90 32 in the housing 1. A similar bushing 33 is provided for a conductor 34 that is connected to the stationary contact terminal 7.

85 A bell-crank lever 35 is operatively connected to the armature 29 of the electromagnet 8 and is connected, at one end, to a spring 36. The latter is operatively connected, at its other end, to one end of a screw-threaded member 37 having a nut 38, by which the tension of the spring 35 may be adjusted 95 and, consequently, the value of current necessary to traverse the winding 26 of the electromagnet 8 to cause the armature 29 to operate is determined.

100 A lip or projecting member 39 on the armature 29, is adapted to engage one end of a rod 40 that is slidably mounted in a bearing member 41 that may be secured to the core

member 28 or be otherwise suitably supported. The other end of the rod 40 fits loosely in one end of an exteriorly-threaded member or nut 42 of substantially cup-shape disposed in the portion 27 of the latching device.

The rod 40 is of composite structure, comprising a tubular insulating intermediate member 43 of fiber or other suitable material and similar metal end members 44. 10 Each member 44 comprises a portion 45 fitted into an end of the member 43, a shoulder 46 engaging the end of the member 43, and an outwardly-projecting portion 47. When actuated by the armature 29, the rod 15 40 moves the member 24 in a counter-clockwise direction for the purpose of releasing the member 10 and, consequently, the movable contact member 16. A pin 48 is mounted on the operating lever arm 9, adjacent to 20 the member 24, and is adapted to move the latter in a counter-clockwise direction when the lever arm 9 is moved in a similar direction. Thus, the interrupter may be tripped, either automatically at a predetermined 25 overload or manually by a relatively small movement of the operating lever 9.

When it is desired to manually trip the interrupter, the lever arm 9 is moved a relatively short distance in a counter-clockwise 20 direction so that the pin 48 will move the member 24 out of engagement with the movable member 10, and the spring 17 will quickly turn the member 10 about the post 13, and, in co-operation with the spring 19, 25 will cause the movable contact member 16 to quickly disengage the stationary contact member 15 with a desirable sliding motion. When a sufficiently large overload traverses the device to cause the armature 29 to operate against the action of the spring 36, 30 the rod 40 will be actuated to cause the movement of the member 24 in a counter-clockwise direction and the disengagement of the contact members 15 and 16, substantially as 35 hereinbefore set forth.

We do not limit our invention to the particular structure set forth, as it may be variously modified without departing from the spirit and scope of the invention, as set forth in the appended claims.

We claim as our invention:

1. In a circuit interrupter, the combination with a movable contact member, a latch for holding the contact member, and means for operating the latch, of means for operatively connecting the operating means and the latch comprising an adjustable member of substantially cup-shape operatively connected to the latch, and a rod extending into the adjustable member and operatively engaging the operating means. 50

2. In a circuit interrupter, the combination with a movable contact member, a latch for holding the contact member, and means for operating the latch, of means for operatively connecting the operating means and the latch comprising an adjustable member of substantially cup-shape operatively connected to the latch, and a tubular rod having inserts at its ends, one of which extends into 60 the adjustable member and the other operatively engages the operating means. 65

3. In a circuit interrupter, the combination with a movable contact member, a latch for holding the contact member, and means for operating the latch, of means for operatively connecting the operating means and the latch comprising an adjustable member of substantially cup-shape operatively connected to the latch, and a tubular rod of 70 insulating material having metal inserts at its ends, one of which extends into the adjustable member and the other operatively engages the operating means. 75

In testimony whereof, we have hereunto 80 subscribed our names this 30th day of Sept., 1919.

HARRY R. MEYER.
LYNN G. RILEY.
